LEWIS EMMONS, OF HAMILTON, OHIO.

Letters Patent No. 73,705, dated January 28, 1868.

IMPROVEMENT IN THE GRATES OF COOKING-STOVES.

The Schedule referred to in these Letters Patent and making part of the same.

TO ALL WHOM IT MAY CONCERN:

Be it known that I, LEWIS EMMONS, of Hamilton, in Butler county, Ohio, have invented a new and useful Improvement in Cooking-Stoves; and I do hereby declare that the following is a full and exact description thereof, reference being had to the accompanying drawings, and to the letters of reference marked thereon.

Figure 1 represents my improvement detached from the stove.

Figure 2 represents a sectional view of the same, as placed in the fire-chamber of the stove.

The object of my invention is to furnish a removable fireplace and deflector for cooking-stoves of any of the usual forms of construction, whereby greater economy in the use of fuel will be attained, and at the same time the means is provided for successfully burning the refuse of fuel, such as fine chips of all descriptions, and bark, cobs, &c.

In the accompanying drawing, fig. 1 represents my removable fireplace, which may be cast of iron in one piece. The ends, A, may be thin castings, or continuations of the fire-back B, or they may be cast in skeleton form, to serve as supports of the fire-back B. The plate which constitutes the fire-back is curved from the rear edge *x* to the line *a*, where it joins the fuel-plate C, which extends in a horizontal plane to the front, upon which the lips *e e* are cast. The front portion of the fireplace, marked D, is provided with suitable openings *d d*, through which the air to support the combustion of the fuel will freely pass. The flange E serves as a deflector of the flame and calorific towards the pot-holes in the top plate of the stove.

My fireplace may be so placed in the fire-chamber of a stove as to rest upon the bottom of the chamber, with its rear edge *x* in contact with the fire-back H of the stove, and may be readily removed, or placed within the fire-chamber through the opening in the top plate of a stove, when the lids and cross-bearer are removed. The apertures 3 3 are for the admission of air to the burning fuel, which will be placed upon the elevated fuel-plate C, and against the curved plate B.

By the use of my improved removable fireplace, a class of fuel may be successfully used which, when placed in the bottom of the fire-chamber of an ordinary cooking-stove, will only remain in a smouldering condition. When the same kind of fuel, consisting of particles of wood chips, &c., is placed upon the elevated fuel-plate C and projecting lips *e*, where there is free admission of air in front, as well as through the series of apertures 3 3 in the plates B and C, the fuel will burn freely, and the flame will be brought in immediate contact with the cooking-utensils on the stove.

When it is desired to use large pieces of wood, my removable fireplace can be taken out of the fire-chamber of the stove for that purpose. But a much less quantity of fuel will be required for summer use by the employment of my invention, because the fire will be brought into close proximity with the articles to be heated or cooked, and the combustion will be greatly promoted.

When the stove is used for baking, the fireplace may be moved forward so as to leave a space in rear of it, next the fire-back H of the stove, as represented in fig. 2. By this arrangement the heat will be allowed to come in contact with the stove-oven at the back of the fire-chamber.

The fireplace may be made only half as long as the fire-chamber of the stove, and have flanges raised at each end, and between the deflector E and fuel-plate C; and when so made the quantity of fuel required will be less, and the heat will be directed to but one of the pot-holes in the top plate of the stove.

It is evident that slight modifications in the construction of my improved fireplace for stoves may be made without departing from the principle of the invention, the leading purpose being to produce a removable fireplace, which will occupy a large portion of the fire-chamber of a cooking-stove, and will elevate the fire upon a suitably-ventilated fuel-plate and fire-back, so constructed and arranged as to insure a free and perfect combustion of fine chips and refuse particles of fuel.

What I claim, and desire to secure by Letters Patent, as my invention, is—

The elevated removable fireplace for cooking-stoves, constructed and used in the manner substantially as and for the purpose described.

In testimony whereof, I have hereunto set my hand, this 9th day of August, A. D. 1867.

L. EMMONS.
